UNITED STATES PATENT OFFICE.

EMIL L. CLAUS, OF MILWAUKEE, WISCONSIN.

IGNITION-TORCH FOR GAS-BURNERS.

1,339,102.

Specification of Letters Patent. Patented May 4, 1920.

Application filed March 18, 1919. Serial No. 283,325.

To all whom it may concern:

Be it known that I, EMIL L. CLAUS, a citizen of the United States, and resident of Milwaukee, in the county of Milwaukee and State of Wisconsin, have invented certain new and useful Improvements in Ignition-Torches for Gas-Burners; and I do hereby declare that the following is a full, clear, and exact description thereof.

My invention relates to new and useful improvements in devices adapted for association with a gas stove to light any one of a plurality of burners thereof when the valve associated with the respective burner has been opened to supply gas to the burner.

It is primarily the object of my invention to render this lighting action automatic in nature whereby, when the valve of any burner is turned on, an igniting torch will be projected toward the burner, thus preventing loss of gas by reason of accidental opening of any burner valve, or by reason of delay in ignition, as when the ignition is under independent manual control, a further object with respect to this automatic action being to simplify the operative steps incidental to use of the stove and to procure a prompt lighting action without necessitating the use of both hands of the operator in procuring such prompt action.

A further and important object resides in the provision of an arrangement whereby, when the gas supply valve of the burner is open, an igniting torch of flame is projected only toward the burner which is opened in contradistinction to existing types of ignition devices, wherein actuation of the device effects the projection of torch flames to all of the burners, which it may at any time be desired to light, this arrangement in existing structures lessening the gas pressure and consequent force and efficiency of the torch which supplies the burner to be lighted.

A further object resides in the provision of an igniter torch head adapted to selectively project igniting jets of gas toward any one of a plurality of burners to be lighted, and wherein means is afforded in a most economical manner for maintaining a pilot light to ignite whichever torch jet is actuated.

A still further object is to embody the foregoing objects and advantages in a structure which is efficient and positive and which may be manufactured and associated with a

conventional gas stove in a most economical manner.

With the above and other objects and advantages in view, which will be apparent as the description proceeds, my invention resides in the novel features of construction, combination and arrangement of parts as hereinafter more particularly described and defined by the appended claims.

In the accompanying drawings:

Figure 1 is a plan view of a gas stove having one embodiment of my invention associated therewith.

Fig. 2 is a plan view of the torch head, the hood being removed.

Fig. 3 is a horizontal sectional view through the lower portion of the torch head on the line 3—3 of Fig. 4.

Fig. 4 is a sectional view showing the torch head and one of the burner valves in operative relation, the plane of this sectional view with respect to the burner head being indicated by the line 4—4 of Fig. 2.

Fig. 5 is a horizontal sectional view through the valve on planes indicated by the broken line 5—5 of Fig. 4.

Fig. 6 is an elevational view of a modified form of burner valve.

Fig. 7 is a detail view of the detent member of said valve.

Fig. 8 is a horizontal sectional view through the modified valve.

Fig. 9 is a diagrammatic view showing a modified arrangement of the torch structure.

Fig. 10 is a detailed view of the preferred valve construction.

Referring now more particularly to the accompanying drawings, 10 designates the top of a conventional gas stove, including in the present instance four burners 11, from which the usual pipes 12 extend to the front of the stove, terminating in air mixing heads 13 into which extend the rear ends of the burner supply valves 14, the forward ends of said valves being threaded in the supply pipe 15 extending along the front of the stove. The usual valve member 16 is mounted in the casing 14, it being provided with a transverse passageway 17 adapted to register with the ports of the valve casing to permit the supply flow of gas to the burner. To provide for a torch supply of gas to the torch head upon actuation of any one of the valve members 16, each valve member is provided with a well 18 communicating with the passageway 17

and having a port 19 extending therefrom adapted to register with an outlet port 20 disposed below the plane of the passageway 17, this outlet port 20 terminating in a nipple to which is secured a tube 21 extending to the torch head. As shown in the detailed Fig. 10, the well 18 may extend through the bottom portion of the valve member and constitute at its lower portion the recess for receiving the usual screw 16' for holding the spring 16" which retains the valve member in snugly seated position, the well being slightly shouldered at the upper end of its screw receiving portion whereby to seat a packing disk 18', preferably formed of lead or other soft metal to insure sealing of the lower portion of the well upon insertion of the spring in assembling the valve. The entire valve structure may thus be readily 15 and economically constructed. By disposing the torch supply port in a plane offset from the plane of the main passageway 17, the desired normal size of the valve member may be maintained, it being noted that the 20 diameter of the valve member and the size of the main supply passageway must be so relatively proportioned as to provide for a desired wide range of swinging movement of the handle of the valve member to effect 25 the open and intermediate position of the valve, avoiding a too sudden opening and closing action.

In the embodiment of my invention shown in Fig. 1, the torch head is disposed centrally of the group of burners 11, and comprises a block or body member 22 having a series of sockets 23 in one side adapted to receive the couplings of the gas supply tubes 21 of the individual burner valves, the sockets being four in number in accordance with the number of burners illustrated. The inner sockets 23 communicate directly with vertical passageways 24, while the outer sockets communicate with convergent passageways 25 terminating at a second pair of vertical passageways 24, the vertical passageways being thus disposed in quadrangular relation. Torch tips 26 are secured in the upper ends of the passageways, each torch tip being provided with a jet aperture 27 adapted to direct the torch diagonally of the series of tips and between a pair of opposite tips toward a respective burner. An independent supply of gas is thus provided for each torch tip, which is controlled by a respective burner valve, and it is understood that each torch tip is supplied with gas from the valve of the burner toward which its jet aperture is directed. 60 It is noted that one of the torches is adapted to project between each pair of tips, thus disposing the inner portions of their paths in closely grouped relation, and means is provided for maintaining a pilot light within 65 the confines of the tips to secure ignition

of whichever torch is actuated. This is most economically effected by providing one of the burner valves with a by-pass passage 31 communicating with the torch supply port 20, flow of gas through the by-pass being controlled by the usual valve screw 32.

The hood for protecting the torch tips and shielding the pilot light from currents of air which might extinguish it, comprises a cylindrical body 28 of such diameter as to receive and snugly fit the upper portions of bosses on the body member through which the torch passageways 24 extend, whereby the hood is thus detachably supported. The torch ports of the hood are formed by drawing portions of the body wall outwardly in tubular shape as shown at 29 in Fig. 4, the projections thus formed serving to deflect currents of air and to drain off fluid which might be spilled from receptacles on the stove and run down the wall of the hood. The upper portion of the hood wall is corrugated to form series of vertical channels in its outer periphery, and a closure cap 30 seats over the corrugated portion of the wall, being provided with projections adjacent its top preventing closure of the upper ends of the passageways of the corrugations. Means is thus provided for venting the upper portion of the hood to avoid the accumulation of dead gases therein which might extinguish the pilot. The entire structure may be most readily cleansed by removing the cap and efficient drainage is afforded which prevents lodgment of matter in the passageways, it being incidentally noted that while the corrugation passageways are shown and described as being formed in the body wall of the hood, they may as well be formed in the wall of the cap 30. It is further noted that any air currents which enter the hood through the vent passageways of the corrugations will be deflected upwardly against the cap and thus broken in force to prevent the possibility of extinguishing the pilot light.

An exceedingly simple, efficient and readily manufactured torch head structure is thus provided, which, while particularly adapted for use in connection with the general igniter device herein described may also be used in connection with other general types of igniters wherein a plurality of jets are to be discharged either singly or simultaneously toward a plurality of burners.

Taking up now the general operation of my improved device, and referring particularly to Fig. 5, it is noted that the valve member 16 of each burner unit is adapted for partial rotation through an arc of slightly more than 90°, rotation through 90° procuring a fully open position of the valve from a fully shut-off position, the torch

ports 19 and 20 being at all times out of registry. A slight rotation past the full open position will then procure registry of the torch supply ports, thus procuring the 5 projection of a single torch jet toward the respective burner, and inasmuch as but a single jet is actuated, a maximum force of projection is procured to insure lighting the burner. The valve member is then 10 turned back slightly to initial full open position, thus extinguishing the torch.

An exceedingly simple structure and operation is thus afforded for automatically lighting any one of the burners of a stove 15 upon swinging movement of the valve of the respective burner to open position, it being noted that in the majority of instances it would not be desired to utilize the maximum flow of gas, and a slight return movement 20 of the valve member would anyhow be effected to procure the desired intermediate position of the valve member for normal cooking operations.

Figs. 6, 7 and 8 show a modified structure 25 wherein means is provided for procuring the torch action at the out-set of opening movement of the valve, thus still further decreasing the danger incidental to accidental opening of the valve and consequent escape of 30 unignited gas into the room. In this structure, the burner valve member 16^a disposed in the usual valve casing 14^a, and provided with a main transverse passage 17^a, has a pair of diametrically opposed torch supply 35 ports 19^a disposed below the passage 17^a and communicating with the well 18^a of the valve member. The torch supply ports 19^a of the valve member are so disposed with respect to the torch port 20^a of the casing 40 that one of said ports 19^a is adapted to register with the port 20^a prior to full registry of the main supply passage 17^a with the main ports of the casing when the valve member is rotated in clockwise direction. In 45 the present structure, the valve member is adapted for continuous rotation in this direction, being provided with a series of radial handle projections 33. Rotation of the valve member in the opposite direction to 50 open the valve is prevented by a pivoted pawl 34 pivoted to and depending from an attachment member 35 which has its upper end bifurcated to embrace the usual forward depending flange 36 of the stove top 10, the 55 attachment member being adjustably secured to the flange by a set screw 38 passed through one of its furcations. This pawl is limited in its downwardly swinging movement by a stop 39 on the attachment 60 member and is thus held in the path of the handle projections 33 of the valve member and in an inclined position, being freely yieldable to permit movement of the handle projections therewith in a clockwise direction of rotation, but preventing movement 65

of the handle projections therewith in a counter clockwise direction of rotation. Thus, assuming that the valve is closed, a partial rotation of the valve member will procure registry of the torch supply ports 70 as the valve begins to open, thus lighting the burner. Movement to full open position is then effected, and the intermediate and subsequent closed position of the valve is procured by a second quarter rotation in the 75 same direction. Thus, whenever the valve is even partially opened, ignition of the burner is assured, counter clockwise movement of the valve member to open position being prevented in the present instance by 80 the pawl 34, although it will be appreciated that any equivalent means may be employed.

In some instances it is not expedient to dispose the torch head at the center of the 85 group of burners, for instance when as shown in Fig. 9 a central burner 11^a is provided. In such instances, a pair of torch heads A are provided at the sides of the stove, each torch head being adapted to supply certain of the burners and being connected by the individual supply tubes 21 with the conventionally shown valves B which control the respective burners. In this arrangement, two of the valves of the 90 stove would naturally be provided with pilot bypasses, one for each of the torch heads. In like manner, the oven burners of the stove may be supplied with automatic lighting means. The specific layout for the 95 oven burners is obvious in view of the foregoing disclosure, and hence not specifically illustrated.

While I have shown and described a preferred embodiment of my invention, it will 105 be appreciated that various changes and modifications of structure may be employed to meet differing conditions of manufacture and use without departing in any manner from the spirit of my invention. It will be 110 further appreciated that various phases of my invention may be used independently of the complete structure described, the torch head structure, for instance, comprising a simple and efficient unit which may be used 115 in connection with any supply means for the jets thereof.

What is claimed is:

1. An igniter device comprising the combination with a plurality of burners and control valves therefor, of a torch head provided with a plurality of upwardly extending torch passageways having lateral jet apertures in their side wall portions each directed toward a certain burner, said jet 120 apertures being closely grouped for ignition by a single common pilot light, means for maintaining a pilot light at said jet apertures, and means operable by each of said 125 burner valves for providing a torch supply 130

of gas through a corresponding passageway.

2. An igniter device comprising the combination with a gas burner, of a torch jet 5 remote from said burner arranged to direct flame toward the burner, and a common valve for controlling supply of gas to the burner and torch jet, including a single valve member operable by continued single

10 movement in one direction to first supply full flow of gas to the burner and then supply gas to the torch jet without substantially affecting full flow of gas to the burner.

3. An igniter device comprising the combination with a gas burner of a torch jet arranged to direct flame toward the burner and a common valve member for controlling supply of gas to the burner and torch jet, 15 said valve member being rotatable from 20 closed position to a position past full open with respect to the burner and said valve member being adapted to supply gas to the torch jet at the said position past full open for the burner.

25 4. An igniter device comprising the combination with a plurality of burners, and valves controlling supply of gas to said burners, of a torch head, means for maintaining a pilot light at said torch head, torch 30 jets carried by the torch head and each directed toward a respective burner and adapted for ignition by the pilot light, and a duct connecting each torch jet with the valve of its respective burner.

35 5. An igniter device comprising the combination with a main gas burner, of a torch jet arranged to direct flame toward the burner, a valve casing, burner and flash ports in said casing having communication 40 respectively with the burner and torch jet and a valve member rotatable in the casing, and provided with supply ports adapted in one position of the valve member for registration with both the burner and flash ports, 45 said valve member being movable from said position to successively shut off supply of gas to the torch port and then to the burner port and means for limiting rotation of the valve member within said limits.

50 6. An igniter device comprising the combination with a plurality of gas burners, of a grouped set of torch jets, each directed toward a certain burner, valves controlling supply of gas to each of the burners, each 55 of said valves including a port connected with the jet for the corresponding burner, said port being adapted to receive gas in a certain open position of the valve, and one of said valves being provided with a bypass 60 therein adapted to maintain a pilot flow of gas to one of the jets for ignition of all of the jets upon actuation of said jets.

65 7. An igniter device comprising the combination with a plurality of burners, of a torch head provided with a plurality of up-

wardly extending torch passageways having lateral jet apertures in their side wall portions each directed toward a certain burner, said jet apertures being closely grouped for ignition by a single common pilot light, 70 means for maintaining a pilot light at said jet apertures, control valves for said burners, each valve having a main burner port and an auxiliary port adapted to receive gas at the same time and a tube connecting the 75 auxiliary port of each valve with a corresponding passageway of the torch head.

8. An igniter device comprising the combination with a plurality of burners and a group of jets, the path of flame of each jet 80 being directed inwardly of the group of jets between an opposite pair of jets and toward a respective burner, means for maintaining a pilot light within the group of jets, and means for supplying torch flow 85 of gas to the jets.

9. In an igniter device, a torch head provided with a series of passages in one side for connection with supply tubes, the head being also provided with a series of vertical 90 passages certain of which communicate directly with the intermediate passages of the first named series and the head being further provided with convergent passages extending from the outer passages of the first 95 named series and terminating at the remaining vertical passages, said vertical passages being thus closely grouped, and torch tips communicating with said vertical passages and each adapted to direct flame diagonally of the group of tips and between a pair of torch tips.

10. In an igniter device, a torch head body member, upstanding bosses on said body member provided with supply passages, torch tips mounted on said bosses and having jet apertures directed inwardly of the group of tips and between a pair of opposite tips, and a cylindrical hood provided with ports in registry with the jet apertures 110 and having its lower portion mounted on said bosses, the spaces between said bosses below the hood being open to supply air to the hood.

11. In an igniter device, the combination 115 with a main gas burner, of a torch jet, a valve casing provided with a burner port and a torch port disposed in a plane offset longitudinally of the casing from the burner port, a valve member rotatable in the casing and provided with a burner supply passage for communication with the burner port and a second passage in the valve member communicating with the burner supply passage and adapted for registry 120 with the torch port during registry of the burner port with the burner supply passage, said torch supply passage being movable from registry with the torch port in closing direction of movement of the valve mem- 125

bers prior to movement of the burner supply passage from registration with the burner port.

12. In an igniter device, a valve casing
5 provided with a burner supply port, and a
torch supply port disposed in a plane offset
longitudinally of the casing from the burner
supply port, a valve member rotatable in
the casing and provided with a longitudinal
10 well and with a transverse passageway
adapted to communicate with the burner
supply port, and a port extending from the
well in a plane offset from the plane of said
main passageway and adapted to communi-
15 cate with the torch supply port of the cas-
ing, said offset port being movable from
communication with the torch supply port
upon rotation of the valve member.

13. In an igniter device, a valve casing
20 provided with an inlet port and a burner

supply port, and a torch port disposed in a
plane offset longitudinally of the casing
from the burner supply port, a valve mem-
ber rotatable in the casing and provided
with a transverse passageway adapted to 25
connect the inlet port and the burner supply
port, said valve member being also pro-
vided with a second passageway extending
from said transverse passageway to a point
of its periphery offset from the plane of 30
said main passageway, said second passageway
being adapted to communicate with the
torch supply port of the casing, and being
movable from communication upon rotation
of the valve member. 35

In testimony that I claim the foregoing I
have hereunto set my hand at Milwaukee,
in the county of Milwaukee and State of
Wisconsin.

EMIL L. CLAUS.
